INVENTOR

UNITED STATES PATENT OFFICE.

FRANK ROOP, OF NORRISTOWN, ASSIGNOR TO I. BOND WATT, JOHN A. THOMSON, JR., WINFIELD S. WOLFORD, AND RICHARD M. POPHAM, ALL OF PHILADELPHIA, PENNSYLVANIA.

CAR-COUPLING.

SPECIFICATION forming part of Letters Patent No. 373,947, dated November 29, 1887,

Application filed August 6, 1887. Serial No. 246,249. (No model.)

To all whom it may concern:

Be it known that I, FRANK ROOP, a citizen of the United States, residing at Norristown, in the county of Montgomery and State of Pennsylvania, have invented a new and useful improvement in Car-Couplings, which improvement is fully set forth in the following specification and accompanying drawings.

My invention relates to improvements in car-couplings; and to this end it consists, first, in a novel form of coupling so devised that it couples automatically and can be uncoupled without passing between the cars.

It consists, second, in a novel arrangement whereby an extra link is carried in the coupling.

It consists, third, in novel features herein-after described, and particularly pointed out in the claims.

Referring to the drawings, Figure 1 is a perspective view of a car-body with my improved coupling attached. Fig. 2 is a side elevation of two couplings in position to be coupled. Fig. 3 is a vertical longitudinal section taken through Fig. 2, with the coupling in coupled position. Fig. 4 is a plan view of my coupling when coupled.

A is a car-body with one of my couplers attached.

B B' are two couplers, which are exact duplicates of each other. These couplers are bell-mouthed, as shown at C, in order to receive the link L from cars of different elevation.

D D' are coupling-jaws, pivoted at E E', and having hooks or catches F F', adapted to fall over a link when two cars come together, as clearly shown in Fig. 3.

Additional bearings, G G', in the nature of lugs or shoulders, are provided, which serve a double function of steadyng the catches and holding the link permanently on one end, as shown in Fig. 3, so that it cannot be lost.

H H' are lugs, which assist in holding the link in place and close against blocks H' on the base of the draw-head.

K K' are ears on the coupler-hook, connected to a rod or chain, M, running to the top of the car, for lifting the coupling-hooks without going between the cars.

N N are shoulders on the coupling-hooks for limiting the throw of the hooks, so that the link L cannot be removed from the coupling, as clearly shown in dotted lines in Fig. 3.

L' is an extra link slid into its back position 55 around the blocks H', so as to be out of the way when not used.

Each coupling has one link, thus making one extra link when the cars are coupled.

The operation is so obvious as to need no 60 further explanation, it being clear that on forcing two cars together the projecting link will force its opposing hook up and allow it to drop into position.

The weight of the jaws is sufficient to tilt the 65 link up on a line, and to thus present it always in a position ready for automatic insertion.

The links L L' are put in place before the coupling-hooks D D' are inserted and the pins 70 E E' fixed in place, after which they cannot be removed without taking the coupler to pieces.

N' is a coupling-lever of bell-crank shape, journaled to the end of the car, and having handles P P, adapted to operate the coupler 75 from the side of the car through the agency of a chain-connection, as shown.

I am aware that automatic car-couplers are old, and that devices have been arranged to couple and uncouple the cars from the side and 80 top of the car without necessitating an entrance between the cars. I do not claim such feature.

I am not aware that any device has been constructed for retaining the links so that they cannot be lost; nor do I know it to be old to devise means to hold the link horizontal while the cars are in uncoupled position, nor to provide an extra link carried in the coupler.

It will be seen that with my device I provide against the loss of links—an item of no small 90 matter in railway matters. I also provide a cheap, simple, and durable coupler adapted to couple automatically any cars of ordinary heights if provided with similar couplers.

Having thus described my invention, what 95 I claim as new, and desire to secure by Letters Patent, is—

1. A car-coupling device consisting of two couplers, each of which is provided with a pivoted jaw having a hook at its front end, a bear- 100

ing in the rear of the hook, and a lug in the rear of the bearing, and a link, substantially as described.

2. A car-coupler having a pivoted jaw with a bearing in the rear of the hook, a lug in the rear of the bearing, and a shoulder above the pivoted axis of the said jaw, substantially as described.

3. In a car-coupling device, a coupler hav-

ing a pivoted jaw with a bearing in the rear of the hook and a lug in the rear of the bearing, said lug closing against the block H² of the coupler, substantially as and for the purpose set forth.

FRANK ROOP.
